UNITED STATES PATENT OFFICE.

JOHN F. COURSON, OF PITCAIRN, PENNSYLVANIA.

DRAFT-GEAR.

1,156,670.

Specification of Letters Patent.

Patented Oct. 12, 1915.

Application filed July 16, 1914. Serial No. 851,272.

To all whom it may concern:

Be it known that I, JOHN F. COURSON, a citizen of the United States, residing at Pitcairn, in the county of Allegheny and 5 State of Pennsylvania, have invented certain new and useful Improvements in Draft-Gears, of which the following is a specification.

My invention consists of an improvement 10 in friction draft gears for railway cars, etc., and has for its object to provide a draft gear of simple construction and high efficiency, designed to utilize the wedging and releasing qualities of friction creating wedge 15 blocks, a central buffing member, a suitable shock absorbing member, and co-operating parts connected with the drawbar, arranged to effect the desired results, either in buffing or pulling, as hereinafter described.

20 A particular object of the invention is to provide, in a gear of this type, means for transmitting rearward strains to the car framing through an interposed shock absorbing device, as a friction or spring gear, 25 or both, either in buffing or pulling. In the construction herein illustrated and described, this effect is produced by means of double acting wedge members and the central buffing wedge, adapted to communicate 30 pressure rearwardly to the shock absorbing member, in combination with an embracing wedging box or housing connected with the drawbar.

In the accompanying drawings, showing 35 preferred constructions, Figure 1 is a horizontal sectional view of the complete draft gear assembled, the parts being in normal extended position, the section being indicated by the line I. I. of Fig. 2. Fig. 2 is 40 a longitudinal vertical section of the gear, indicated by the line II. II. of Fig. 1. Fig. 3 is a transverse sectional view, indicated by the line III. III. of Fig. 2. Fig. 4 is a horizontal sectional view, similar to Fig. 1, 45 showing the action of the gear in pulling. Fig. 5 is a collective detail view in perspective, showing the co-acting compound wedges for engagement with the wedge box and central buffing wedge. Fig. 6 is a similar view of the wedge box. Fig. 7 is a longitudinal sectional view, partly in elevation, 50 showing the application of the wedging mechanism to an ordinary buffer spring.

In the drawings, 2 represents the drawbar 55 of the coupler fixedly connected with the wedge box A by a transverse key 3 extend-

ing through the rear end of the drawbar and by its terminals through the slots 4 of connecting links 5. Said links are connected by slots 6 with the lugs 7, extending outwardly at each side of the wedge box A. Lugs 7 are preferably provided with rearwardly extending lips, as shown, whereby to overlap the rear ends of links 5 and prevent separation of the parts.

Extending transversely of the center sills *a* and through openings therein are the cross bar members or keys 8, similar cross bars 9 being secured to the sills *a* in any suitable manner, as by riveting. These 70 keys 8 and 9 define by their inner faces guiding ways for the drawbar 2, and also provide, by their rear edges, bearings for the transverse follower 10. Said follower is preferably provided above and below with 75 overlapping lips 11, embracing the keys 8 and 9, and at their rear with lips 12, adapted to receive the compound wedges B, B, which co-operate with the wedge box A. Wedges 80 B are provided at their outer middle portions with longitudinal recesses 13 for reception of the links 5, and above and below such recesses are widened, providing for the wedge faces 14 which co-act with the interior wedge faces 15 of wedge box A.

At their inner sides wedge members B are provided with inwardly extending wedge members 16 having inner oppositely diverging faces 17, adapted to co-act with the wedge faces 18 of the central buffing wedge 90 member 19. Said buffing wedge member extends through an opening 20 centrally of wedge box A, and backwardly to operative position with relation to the shock absorbing elements of the shock absorbing member D. 95 Said member, which may be of any suitable construction, embodying spring gear or friction gear mechanism, or both, is rearwardly of the mechanism just described, between the center sills *a*, *a*, and abuts by 100 its rear end directly against a transverse block or abutment 21 and is supported in position by any suitable means, as a strap 22.

Central buffing wedge 19, as shown, is provided with rear wedge faces 23 co-acting 105 with the wedge mechanism of member D, not necessarily herein described, and wedge box A is provided with rearwardly extending lugs 24 engaging the front edge portion of member D and firmly bracing thereagainst in buffing strains. Central buffing wedge member 19 interfitting between faces

17 of wedge member 16 of elements B, is preferably provided with extensions 25, whereby to maintain it centrally in position between the top and bottom walls of wedge box A.

In Fig. 7 I have shown a modified construction in which the parts corresponding to those above described are similarly marked with the exponent'. In such construction, a shock absorbing spring D' abuts rearwardly against the transverse bearing 21' and is engaged at its front by the rearward extension 24' of wedge box A', connected by links 5' with the drawbar 2'. 10 15 Wedge box A', in such construction, co-acts with the compound wedges B' in the same manner as above described, said wedges bearing by their front ends against the follower member 10'.

20 The operation of the invention is as follows: In buffing, follower 10 is thrust backwardly, carrying with it wedges B, against the inwardly converging faces 15 of wedge box A, thus effecting inward and approaching movement toward each other of wedge members B. Thereupon their faces 17 acting on faces 18 of central buffing wedge 19, thrust it backwardly, compressing the resisting mechanism in member D, and transmitting strains rearwardly therefrom to the car framing. In pulling, forward travel of links 5, as in Fig. 4, by drawbar 2, draws wedge box A forwardly, its wedge faces 15 engaging faces 14 of wedges B, causing 25 30 35 them to approach each other, and effecting by their faces 17, acting on faces 18 of central wedge block 19, rearwardly of said member, transmitting rearward movement to member D and the car framing in the 40 same manner. It will thus be seen that with either buffing or pulling, and independent of the construction of the shock absorbing member D or D', either operation will effect rearward action against such 45 member and resulting transmission of the strains uniformly in a rearward direction.

It will be understood that the angle of inclination of the several wedge members is a matter of design or adjustment to be determined by the varying conditions in application or service of the gear, and that all such features or details of construction, or others, are within the province of the skilled mechanic and intended to be included within 50 55 the scope of the appended claims.

The gear in its entirety is very compact and powerful, composed of few parts, and is easily installed or removed, and develops a very high capacity in opposition to either 60 normal or abnormal shocks incident to car service.

What I claim is:

1. In a friction draft gear, the combination with car framing, of a shock absorbing element adapted to transmit strains to the 65 car framing, a drawbar, and intervening co-acting face-to-face wedge mechanism embodying plural faced wedge members, some of said members having alternating overlapping portions, a central buffing wedge, 70 an embracing wedge box, and means connecting said box to the drawbar.

2. In a friction draft gear, the combination with car framing, of a shock absorbing element adapted to transmit strains to the 75 car framing, a drawbar, and intervening co-acting face-to-face wedge mechanism embodying plural faced wedge members, a central buffing wedge, an embracing wedge box, and links connecting the wedge box with 80 the drawbar.

3. In a friction draft gear, the combination with car framing, of a shock absorbing element adapted to transmit strains to the 85 car framing, a drawbar, transverse stops, a follower, laterally movable wedges abutting forwardly against the follower, a co-acting wedge box embracing said wedges, means connecting the wedge box and drawbar, and a central member adapted to transmit movement from the laterally movable wedges to the shock absorbing element. 90

4. In a friction draft gear, the combination with car framing, of a shock absorbing element adapted to transmit strains to the 95 car framing, a drawbar, transverse stops, a follower, laterally movable wedges abutting forwardly against the follower, a co-acting wedge box embracing said wedges and abutting rearwardly against the shock absorbing element, means connecting the wedge box and drawbar, and a central member adapted to transmit movement from the laterally movable wedges to the shock absorbing element. 100

5. In combination, a shock absorber operatively mounted in car framing, a drawbar, a follower, transverse stops, and wedge mechanism between the follower and the shock absorber comprising a wedge box connected to the drawbar, plural co-acting wedges within the wedge box, and a central buffing wedge engaging said wedges and extending rearwardly through the wedge box and engaging the shock absorber. 110

In testimony whereof I hereunto affix my signature in the presence of two witnesses.

JOHN F. COURSON.
